SUCTION CLEANING APPARATUS

William A. Ardito, West Springfield, and Jack Pickford, Springfield, Mass., assignors to Westinghouse Electric Corporation, East Pittsburgh, Pa., a corporation of Pennsylvania

Application April 1, 1950, Serial No. 153,378

4 Claims. (Cl. 183—44)

1

This invention relates to suction cleaners, and more particularly to cleaners of the type comprising a cylindrical tank or casing containing a motor-driven suction fan and a dust-collecting filter bag.

An object of the present invention is to provide a cleaner of the aforementioned type having a removable dust-collecting filter bag adapted to be readily clamped within the dust-receiving chamber of the cleaner casing.

Another object is to provide a tank type cleaner having a removable dust-collecting filter and an auxiliary disposable filter which may fit into the first-named filter.

Another object is to provide a flexible sealing means for the open intake end of the filters, so designed that it seals the filters when they are in their operating position and prevents dust-laden air from contacting a marginal portion adjacent the open end of the disposable filter bag.

The sealing means is constructed so that the disposable filter bag may be easily inserted and removed from the first-named filter bag of a tank type cleaner.

Other objects and advantages of the invention will appear in the following more detailed description thereof taken in connection with the accompanying drawings in which:

Fig. 1 is a side elevational view, partly in section, of a suction cleaner embodying the invention;

Fig. 2 is a fragmentary side elevational view similar to Fig. 1, showing certain parts separated;

Fig. 3 is a perspective view of the sealing gasket having a portion removed to show more clearly its construction; and

Fig. 4 is an enlarged fragmentary view, in section, showing certain details of the invention.

Referring to the drawings in detail, a suction cleaner equipped with a filter bag and a sealing gasket constructed in accordance with the invention is shown as comprising a cylindrical casing 10 closed at one end by a separable front head 11 having a suitable intake opening 12, and at the other end by a rear head 13 having a suitable exhaust (not shown).

The casing 10 contains the usual motor-driven fan assembly 14 and is adapted to be disposed in a horizontal position and to rest on a pair of runner members 15. The fan assembly 14 draws dust-laden air through the intake opening 12 provided in the head 11 and into a filtering chamber 16, formed in the casing 10, adjacent the head 11.

2

As shown more clearly in Fig. 4, the end of the casing 10 to which the front head 11 is secured is provided with an inwardly bent annular flange 17 with which an annular clamping face 18 of the head 11 is adapted to be aligned when the head is secured in its normal operating position.

The cleaner includes a conventional porous cloth filter bag 24 having a ring 21 secured thereto at the mouth or open end by means of wires 25. The ring 21 has a flange 20 extending radially outwardly therefrom. A sealing gasket 19, as shown in Figs. 3 and 4, is provided with a groove 22 adapted to receive therein the flange 20 of ring 21, and with an integrally formed depending flexible portion 23, which may be of bulged form as shown.

The bag 24 with its ring 21 and the sealing gasket 19 may readily be removed from the cleaner, when the front head 11 is detached from the casing as shown in Fig. 2.

A cylindrical filter bag 26 made of porous material such as paper is designed to fit snugly within the bag 24, as shown in the drawings. The paper bag 26 is of the disposable type and may be removed from the cloth bag 24 and discarded. The bag 26 is made long enough to provide a portion 27 at its open end extending beyond the bag 24 and its ring 21. The extended portion of the bag 26 is adapted to receive a member 28, which is carried by the head 11 on the inner side thereof and which is dished shaped so that the extended bag portion 27 fits snugly over the cylindrical exterior surface of the member 28, as best shown in Fig. 4. The member 28 is provided with a flange 29 received within a recess 30 of the head 11 and is secured therein by a compressed sealing gasket 31.

Suitable clamping means may be employed to secure the head 11 to the casing 10 and to exert pressure on the sealing gasket 19. Such clamping means as herein illustrated are well known and in the form here shown, the casing 10 is provided with a hinge pivot 32 on the underside and a spring-biased toggle clamp 33 mounted on the upper side. A compression spring 34 carried by the head 11 exerts pressure between the head 11 and a hinge member 35 slidably mounted on the head 11 by a stud 36. As shown in Fig. 4, the toggle clamp 33 has a compression spring 37 exerting pressure on a clamping member 38 having its turned end 39 secured in a recess 40 provided in the head 11.

The function of the sealing gasket 19 is to prevent air leakage between the detachable

head 11 and the casing 10, to provide a seal between the ring 21 and the casing, and also to prevent dust from collecting on the extended portion 27 of the disposable filter bag 26. To this end, the dependent portion 23 of the gasket 19 is normally biased outwardly, as shown in Figs. 2 and 3, to permit the easy insertion of the disposable paper bag 26 in the cloth bag 24. The portion 28 of the head 11 is inserted in the free end portion 27 of the paper bag 26 and the clamping means described above is employed to fasten the head 11 to the casing.

As the head 11 is fastened to the casing, the peripheral portion of the gasket 19 is compressed between the clamping face 18 and the flange 17. The clamping face 18 deflects the depending flexible portion 23 toward the flange 20 and radially inwardly against the cylindrical surface of the member 28, to retain the paper bag 26 against such cylindrical surface. The gasket 19 also forms a seal between the ring 21 and the member 28.

From the foregoing it will be seen that according to the invention, a suction cleaner of the tank type is provided so constructed as to prevent dust-laden air from entering the space 43 between the gasket 19 and the gasket 31 of the head 11. Thus, my improved sealing gasket effectively seals the extended portion 27 of the paper bag from dust-laden air. When the bag 26 has become filled with dust, the head 11 is removed and the disposable bag 26 may be removed from the cloth bag 24 by the operator lifting the disposable bag from the cleaner by the extended, unsoiled portion 27.

The construction here shown is such that the two filter bags may be used simultaneously, or the cloth bag alone may be used.

While we have shown our invention in but one form, it will be obvious to those skilled in the art that it is not so limited, but is susceptible of various changes and modifications without departing from the spirit thereof.

What we claim is:

1. A suction cleaner comprising a casing having an open end, a gasket supported by said casing adjacent said open end, a head or closure member adapted to close said open end of said casing, said head having a projection on its inner side, which projection has a cylindrical exterior surface extending within said gasket in closely spaced relation thereto, and means for clamping said head to said casing, said gasket being deformed by said head to bear radially in-

wardly against said cylindrical exterior surface of said projection.

2. A suction cleaner comprising a casing having an open end and an inturned flange adjacent said open end, a head or closure member adapted to close said open end of said casing, a cloth filter bag having a ring attached to its open end, said ring comprising a flange extending radially outwardly, a gasket embracing the outer edge of said ring flange and adapted to engage said casing flange, said gasket further comprising a bulged portion extending radially inwardly adjacent the outer face of said ring flange, said head having a projection on its inner side, which projection has a cylindrical exterior surface extending within said ring in closely spaced relation thereto, and means for clamping said head to said casing, said head having an annular portion which, when the head is clamped to the casing, bears upon said gasket and forces it radially inwardly against said cylindrical surface of said projection.

3. A suction cleaner comprising a casing having an open end and a gasket-supporting seat adjacent said open end, a head or closure member adapted to close said open end of said casing, a dust-collecting filter bag having an open end, said head having a projection on its inner side adapted to enter the open end of said filter bag to hold the same distended, and a gasket adapted to bear against said seat of the casing, said head having an annular portion which, when the head is clamped to said casing, bears upon said gasket and forces it inwardly against the outer surface of said bag to clamp the same between said gasket and said projection.

4. A suction cleaner as set forth in claim 3 wherein said head or closure member has a recess extending inwardly thereof from said gasket and around said projection to receive the open end portion of said filter bag.
